UNITED STATES PATENT OFFICE.

ARTHUR C. DAVIDSON, OF CHICAGO, ILLINOIS, ASSIGNOR TO WAUGH DRAFT GEAR COMPANY, OF CHICAGO, ILLINOIS, A CORPORATION OF ILLINOIS.

ANTIFRICTION DRAW-BAR SUPPORT.

1,342,586.

Specification of Letters Patent. Patented June 8, 1920.

Application filed April 12, 1916. Serial No. 30,559.

To all whom it may concern:

Be it known that I, ARTHUR C. DAVIDSON, a citizen of the United States, and a resident of the city of Chicago, in the county of Cook and State of Illinois, have invented certain new and useful Improvements in Antifric-
5 tion Draw-Bar Supports; and I do hereby declare that the following is a full, clear, and exact description of the same, reference
10 being had to the accompanying drawings, and to the numerals of reference marked thereon, which form a part of this specifi-
cation.

One of the sources of almost constant at-
15 tention in the maintenance of rolling stock
is the wear of the drawbar upon the guiding
or supporting means provided therefor.
This is occasioned by the continuous longitudi-
20 nal movement of the drawbar when a car
is in motion, due to the movement of the
parts of the draft gears of the coupled cars.
The wear between the drawbar and its sup-
port is due to the fact that a sliding move-
25 ment is permitted to take place between the
parts, and this of course, due to the fact
that such movement takes place, almost con-
tinuously when a car is in use, soon causes a
serious amount of wear to take place. By
30 my invention a rocking contact is provided
for the drawbar upon means which support
the same in proper horizontal position for
coupling, thus obviating, to a large extent,
wear upon the parts.

It is an object therefore of this invention
35 to construct a drawbar supporting mechanism
comprising movable means capable of
rocking contact with the drawbar to support
the same in proper position on the car and
permitting longitudinal movement of the
40 drawbar to take place without undue wear
upon the parts.

It is also an object of this invention to
construct a drawbar supporting means
45 adapted to be rigidly connected to the sills
of a car, affording a rocking contact for sup-
port of the drawbar and maintaining the
same properly positioned in all adjustments,
due to movement of the parts of the draft
gear.

50 It is furthermore an object of this inven-
tion to provide a drawbar supporting mech-
anism comprising a casing adapted to be
rigidly attached upon the sills of a car, and
having mounted therein a rocker upon which
55 the drawbar rocks in its longitudinal move-

ment whereby the drawbar is supported in
proper position in all adjusting movements
thereof.

It is finally an object of this invention to
construct a device simple in operation and
60 construction and operating efficiently to per-
form the purpose.

The invention (in a preferred form) is
illustrated in the drawings and hereinafter
more fully described. 65

In the drawings:

Figure 1 is a fragmentary detail view
illustrating a device embodying the prin-
ciples of my invention in section, and showing
the same supporting the drawbar on a car. 70

Fig. 2 is an enlarged sectional detail of the
device similar to the illustration thereof in
Fig. 1.

Fig. 3 is a top plan view of the device,
with the drawbar broken away and the sills 75
of the car shown in section.

Fig. 4 is a detail view taken on line 4-4
of Fig. 3, with parts in section.

Fig. 5 is a section taken on line 5-5 of
Fig. 3. 80

As shown in the drawings:

The reference numeral 1, indicates as a
whole the end of a car of any conventional
type, and provided, as shown in Fig. 3, with
longitudinal center sills 2, the lower flanges
3, of which are tapered toward the forward
end of the sills. The drawbar is denoted
as a whole by the reference numeral 4, and is
provided on its outer forward end with a
coupler head or drawhead 5. 90

The device embodying the principles of
my invention is attached upon the center
sills 2, and consists of a heavy casting 6, pro-
vided with integral hooked bracket arms or
webs 7, on each side at the rear thereof, 95
which, as clearly shown in Figs. 3 and 5, are
wedgingly engaged over the outer flanges 3,
of the sills in interfitting relation therewith.
At the forward end of the casing or casting
6, a tubular or cylindrical portion 8, is 100
formed extending transversely thereacross,
and inserted therethrough is a retaining bolt
9, which also engages through registering
apertures provided for the purpose in the
webs 2, of the sills, the flanges 3, being cut 105
away at this point for the purpose, and re-
taining nuts 10, are provided on the outer
ends of said bolt to lock the parts in assem-
bled relation.

Within the casing or casting 6, which is 110

cored out for the purpose, is disposed a rocker 11, which consists of an I-beam section having an upper rounded surface 12, and a lower rounded surface 13, said surfaces being curved about a common axis. As clearly shown in Figs. 2, 4, and 5, the cylindrical sector 11, is provided with vertical ribs or webs 14, disposed at right angles thereto to reinforce the same. The interior 10 of the casting or casing 6, is provided with a hardened horizontal partition or bearing floor 15, upon which the lower surface 13, of the rocker rocks, and recesses 16, are provided through said bearing floor to permit 15 outlet therethrough of any foreign matter which may find entrance into the casting at the upper end.

The operation is thought to be obvious from the description. However, longitudinal 20 movement of the drawbar 4, due to movement of the elements of the draft gear on which the same is connected in the usual manner, is allowed to take place, due to the fact that the drawbar rocks upon the rocker 25 11, which in turn rocks upon the floor 15, within the casting or casing 6. The construction is extremely simple, the rocker merely being inserted into the casting provided therefor. No auxiliary retaining 30 means are necessary to hold the rocker in place, the weight of the drawbar resting thereon on the upper surface thereof insuring retention thereof in the casing at all times. The casing is attached upon the center sills of the car in an easy manner facilitating ready removal or attachment thereof, the bracket members 7, merely being wedged into engagement with the bottom flanges 3, of the sills, by movement of the device rearwardly thereon and the bolt 9, is inserted 35 through the registering apertures provided in the sills and the cylindrical forward portion of the casing to lock the same in place. The rocker element 11, is so constructed that the same acts normally to tend to move to a centered or upright position, such as shown in full lines in Figs. 1 and 2.

I am aware that various details of construction may be varied through a wide 50 range without departing from the principles of this invention, and I therefore do not purpose limiting the patent granted otherwise than necessitated by the prior art.

I claim as my invention:

55 1. In a device of the class described, the combination with a car and drawbar, of means for supporting the drawbar in proper relation with the car comprising a casting, means integrally formed on the front and sides thereof adapted to rigidly secure said casting to the car, and means mounted within said casting upon which the drawbar is movably supported.

60 2. In a device of the class described for supporting a drawbar beneath the car, a

casting adapted to be rigidly secured to the car, and an I-beam rocker mounted transversely within said casting extending transversely beneath the drawbar, said rocker having curved upper and lower surfaces 70 permitting the drawbar to rock thereon while supported in substantially the same horizontal plane.

3. In a device of the class described for attachment on a car to support a drawbar 75 to permit longitudinal movement thereof, a casting, hooked means thereon to engage over the lower flanges of the sills of the car, mechanism interlocking the casting with the sills of the car to hold the same rigidly 80 locked and thereby supported therefrom, and means disposed within said casting adapted to support the drawbar thereon.

4. In a drawbar support of the class described the combination with a car and 85 drawbar, of a casing adapted to be secured to the sills of the car, and an I-beam rocker disposed therein to movably support the drawbar in proper position on the car.

5. A draw bar support comprising an I 90 beam member having oppositely disposed convex faces.

6. A rocker support for draw bars comprising a rocking I beam member and a support for the I-beam member at the base 95 thereof.

7. A rocker support for draw bars comprising a rocking I beam member, reinforcing ribs secured to said member and a support under the I-beam member engaging the 100 base thereof.

8. In a device of the class described a casing and an I beam member loosely supported thereon to rock back and forth with the draw bar supported thereon. 105

9. In a device of the class described, the combination of an upright tilting member adapted to swing from side to side, and provided with a longitudinal bearing at the top and a longitudinal bearing at the bottom 110 thereof, a draw-bar extending transversely across the upper edge of the tilting member and supported thereby, and supporting means provided with a longitudinal bearing part engaging the lower edge of the 115 tilting member, said supporting means shaped to limit the swing of said tilting member.

10. In a device of the class described, the combination of an upright tilting member 120 adapted to lean from side to side, a support provided with a longitudinal bearing engaging the lower end of the tilting member, a draw-bar resting on and extending transversely across the upper edge of the tilting 125 member, said support embracing means adjacent the upper edge of the tilting member for limiting the tilting movement thereof.

11. In a device of the class described, the 130

- combination of a recessed support, an upright oscillating member mounted in the recess of the support, the said support being provided with V-shaped means suitably spaced at the base of the recess and expanded at the top thereof to limit the oscillation of the oscillating member.
12. In a device of the class described, the combination of a support provided with a longitudinal recess, an oscillating member provided with a longitudinal bearing edge engaging the recess, the said support being provided with confining means at the base of the recess adapted to engage the lower portion of the oscillating member and being provided with expanded portions adjacent the top of the oscillating member for limiting the oscillation thereof, and a draw-bar supported by the oscillating member.
13. In a draw-bar support, the combination of a supporting member having a longitudinal V-shaped groove, an oscillating member having the lower edge thereof seated in the groove and the upper edge thereof projecting above the walls of the groove, 25 and a draw-bar supported on the upper edge of the oscillating member.
14. In a device of the class described, the combination of a standard draw-bar having a flat lower bearing surface, of an oscillating member engaging the flat lower bearing surface of the drawbar, a supporting means extending axially across under the said oscillating member, and means at each side of the oscillating member for limiting the 30 oscillation thereof.
15. In testimony whereof I have hereunto subscribed my name in the presence of two subscribing witnesses.
- ARTHUR C. DAVIDSON.
